REPAIR OF RAIL JOINTS IN TRACK

George Langford, Joliet, Ill., assignor to McKenna Process Company of Illinois, Joliet, Ill., a corporation of Illinois

Application August 10, 1933, Serial No. 684,527

2 Claims. (Cl. 238—164)

My invention has to do with railroad track and more particularly with the repair of track joints after they have become worn. I employ a method of repairing the worn joints in the track to avoid taking up the rails, and so that repairs can be made better and more easily than ordinarily, thereby encouraging first-class upkeep of track and not permitting it to reach a rough riding and unsatisfactory condition.

10 My invention is an improvement on my Reissue Patent No. 17,743 reissued July 22, 1930 out of the original Patent No. 1,670,515, filed August 27, 1927 and issued May 22, 1928.

15 The present invention is to some extent a specific application of the method shown in my Reissue Patent 17,743, with the addition that the bar is designed to make novel use of certain conditions present in the worn rail ends. The combination, as I will explain further, produces certain new and useful results which will be readily understood by those familiar with the art from the following description and accompanying drawing, in which:

20 Figures 1 to 6, inclusive, are side and end views of fragmentary upper portions of worn rail joints illustrating the prior art of repairing them by rail-top welding and the use of specially shaped bars;

25 Figure 7 is a side view of an ordinary worn rail joint;

30 Figure 8 is a side view of a worn rail joint being repaired according to the present invention;

35 Figure 9 is a side view of a worn rail joint fully repaired according to the present invention.

40 The present invention is in accordance with the increased attention now being given by railroad engineers to the upkeep of rail joints. Rough riding track is due largely to worn joints, and to maintain smooth riding track the joints must be not only in first-class condition originally, but must be kept so.

45 In times past, it was accepted as an unavoidable evil that in spite of ordinary care and attention, rail joints would wear and become "low" or depressed under load and the tops of the rail ends become battered, finally necessitating taking up the rails for removal to rerolling or coldsawing plants where a foot or more of each battered end would be cut off. This method was troublesome and costly, and not satisfactory. With the advent of "torch welding" came a new practice as illustrated in Figure 1 which is a side view of the fragmentary portions of two worn rail ends 1 and 1' repaired by welding new metal 3—4—5 and 55 3'—4'—5' onto their tops by a torch 6, the sur-

faces 3—5 and 3'—5' being restored to substantially their original level. Figure 2 is an end view of rail end 1 showing the metal welded on to a depth 5—4 at the extreme end. As far as track surface not under load is considered, the joint 5 was apparently thus put in first-class repair.

However, when under load the repaired joint became depressed because of fishing surface wear. As is well known, the fishing surface wear of a joint occurs for a restricted length at its center portion, there being little or no wear at the end portions. In Fig. 3, a fragmentary side view of the upper half of a worn rail joint, the tops of the rail ends are depressed as in Figure 1. There is also fishing surface wear 8—7—7'—8'—9, part 15 of which is fishing wear of the joint bar, the balance being fishing wear on the under head surface of each rail end. The heads of the rail ends being unsupported yield under load making rough riding track, even though the rail-head tops be 20 repaired by the welding on of metal as in Figure 1. As a partial remedy, the worn joint bars were replaced with new ones of ordinary type, but although this compensated for wear of the bar, the wear of the rail ends 8—7—7'—8' still left 25 the rail-heads unsupported, permitting depression of the joint under load as before and rapid deterioration.

My Reissue Patent 17,743, previously referred to, aimed to remedy this. To compensate for 30 the fishing wear of the rail ends as well as the corresponding fishing surface of the bar, the common type of bar ordinarily used was replaced by a bar crowned to above normal fishing height as its center portion to compensate for the fishing 35 surface wear of the rail ends as well as that of the bar. Metal was then welded onto the tops of the rail ends to a level surface. This method is shown in Figure 5, which is a side fragmentary view of the upper half of a repaired rail joint. 40 Although less than at the top, there is also rail and bar fishing wear at the bottom of the joint. The drawings of my Reissue Patent 17,743 illustrate the wear at bottom and the bar is crowned there as at the top to compensate for rail and bar 45 fishing surface wear at bottom, making, theoretically at least, a completely repaired rail joint.

However actual practice was a departure from this method. The great bulk of bars reformed by me were not intentionally crowned at the bottom, the reforming dies being designed to make the bottom fishing surface straight; that is, to make the bottom fishing surface in one plane throughout its length. The resultant bars were presumably straight inasmuch as the reforming 55

dies were made so, but gradually it became apparent that many of these bars were accidentally crowned or irregular at the bottom, due to the variability in the reforming pressure resulting 5 from various conditions of wear. The uncertainty of results in track suggested greater uniformity in the bottom fishing surface of the reformed bar, an improvement made possible by the method of reforming disclosed in my Reissue 10 Patent 18,165, reissued August 25, 1931 from the original Patent No. 1,712,506, filed March 20, 1929, the latter forming a divisional application from one filed July 16, 1926. This is a method of applying indirect pressure so as to reform properly 15 the bottom fishing surface of a bar. To insure uniformity in the top fishing surface, I employed a method disclosed in my Patent No. 1,808,468, filed March 24, 1930 and issued June 2, 1931, this being a divisional application out of an original 20 filed April 10, 1929. With these methods I secured satisfactory results. Many of these bars were used in conjunction with rail top welding, to effect the complete repair of a worn rail joint, but in a novel manner, due largely to the design 25 of the bottom fishing surface and its relationship to the worn rail ends. As is well known, it is a difficult thing to prove the practical advantages of new types of bars, and as a rule, these must be determined from the results secured in actual 30 service, these results in the present instance becoming more clearly defined, the more closely I maintained the bottom fishing surface of the bar to a predetermined design. It is now obvious that new and valuable features previously appearing occasionally in joints repaired with 35 crowned bars, were due mainly to the bars of a predetermined design thereby accomplishing a new and useful result. This design is directed particularly to the bottom fishing surface of the 40 bar for use on worn rail ends.

Figure 7 is a side view of a worn rail joint whose upper portion is similar to that shown in Figure 3. An examination of the lower portion shows that the joint as a whole is depressed, the 45 rail ends being slightly drooped or bent downward in what appears to be a permanent set, for a mere tamping up of the joint ties does not restore the top of the rail ends to a permanent level. Bars have been designed to lift the 50 drooped rail ends, but I know of none that have any control over lifting too much, so as to make the repaired joint too high instead of too low, as it was before. To make smooth-riding track, the tops of the rail ends when under load should be 55 level. The bar used in my invention raises the drooped rail ends to a predetermined height. Once the bar is bolted up and the joint repaired, it is impossible to transform it into a too high joint, this control not being present, as far as I 60 am aware, in any other bar designed to raise drooped rail ends.

In speaking of a crowned bar, I mean a bar having at least one of its top and bottom fishing surfaces higher at the center than at the ends, 65 and the fishing height of the bar greater at its center than at its ends. Inasmuch as I aim to reduce or at least not to increase the number of surfaces abrading upon one another in the joint, it is important that the crowned surface be not 70 a separate piece but an integral part of the bar itself. In present day track made of steel rails fastened to wooden ties, there is always a wave motion or progressive deflection in the rails under heavy train loads, and this wave motion occasions 75 some movement of the joint bars upon the rail

ends. For this and other reasons it is not desirable to repair the joint wear of important track with patches or liners, each one of which presents two more abrading surfaces, an increase of 50% over the four wearing surfaces already present in a bar in a joint. My method of repairing a worn joint has all of the changes necessary included integrally in the bar itself so as to avoid the necessity for any patchwork or multiplicity of abrading surfaces. 10

To facilitate an understanding of my further description, it should be borne in mind that my invention employs a bar having top and bottom rail fishing contact throughout its length or at least for substantial lengths of its end portions 15 and center portion sufficient to meet the requirement of moment length. When finally bolted tight to the rail ends, the bar because of its center and end fishing engagement, is rigidly secured in the joint. Certain other types of 20 joints provide for rail fishing contact clearance at the center portions or end portions of one or both fishing surfaces permitting variations in their functions by manipulations of the joint bolts, particularly the end ones, after the joint has been 25 in service. The bar used in my invention does not perform them, as I will explain. In the prior art, bars designed for use on worn rails, have in some instances taken note of bottom fishing wear in a joint and the reformed bar was crowned 30 at bottom to compensate for the bottom wear of both the bar and the rail ends. The figures of my Reissue Patent No. 17,743 are so drawn. The prior art has also figured bars crowned at the 35 top only, but such figures have disclosed in effect nothing more than that the bottom fishing wear is comparatively slight and may be disregarded. Whether the bar is perfectly straight or not at bottom is not defined, and in no respect is there 40 disclosure of any advantageous results to be 45 gained by the use of a straight bottomed bar on worn rail ends. The present invention herein completely discloses the peculiar advantages 50 gained by a bar uncrowned at bottom, used in conjunction with the bottom fishing surfaces of 55 worn rail ends. This advantage is a final lifting of the drooped rail ends to overcome their permanent set and to restore the drooped rail ends to substantially their original level.

In Figure 7, it will be seen that there is a gap 50 11—18—11'—12—12' at the bottom of the worn joint, due to the droop of the rail ends and to the wear of the bar and rail fishing surfaces. Fishing surface wear at bottom is ordinarily less than at the top, so much so that in the past, bar 55 reforming practice was directed to the top fishing surface of the bar, the wear of the bottom fishing surfaces of bars and rails being considered slight and of no great consequence, seeing that the reformed bars were not being used in important 60 main lines but in secondary track. However there has grown to be a demand for greater accuracy in reformed bars; and the matter of repairing joints while in track is now receiving extraordinary attention, this applying to main lines as well 65 as less important track, torch welding being a large factor in such repair work. My invention greatly reduces, and, in some cases entirely dispenses with the ordinary welding on of metal to the tops of the rail ends. 70

The bar used in my invention is a crowned bar so designed that it will have top and bottom fishing contact with worn rail ends at its center portion and end portions when finally bolted tight to the rail ends. The bar is crowned on its top 75

surface only so as to make the fishing height above normal at the center portion of the joint. An independent feature of the bar is that its bottom fishing surface is uncrowned; not theoretically straight and actually crowned as I have experienced, but actually uncrowned so as to secure a new and useful result in its application and relation to the bottom fishing surface of worn rail ends. Such a bar is shown at 10 in Figure 8 which is a side view of the worn joint of Figure 7 wherein the worn bar has been replaced by the reformed bar of my invention. The reformed bar of Figure 8 is fitted to the worn rail ends but the bolts are not yet finally tightened up. 15 Before describing my invention fully, I wish to make clearly understood that all of the figures in the drawings have their conditions of joint wear purposely exaggerated as can be readily seen by those familiar with the art. The depths of wear 20 on the tops of the rail ends and on the central fishing surfaces of the bars and the rail ends are really much less than shown, and the depression or "droop" of the rail ends is less, also longer and less abrupt. The figures are intended to emphasize the damage done by wear and my method of repairing it. That amounts of wear small in vertical measurement do great damage is well known by users of rail joints. It is not my intention to encourage the repair of joints as badly 25 worn as the drawing indicates but to maintain them before extreme wear occurs, although this does not preclude repairing even badly worn joints to first-class condition.

In fitting up the bar to the rail ends, the first 30 step of which is shown in Fig. 8, the top fishing surface of the bar first contacts the rail ends at the crown 8—1—1'—8', the bottom fishing surface engaging with the rail ends at its ends. Due to the droop in the rail ends and their bottom fishing wear, there will be space 11—18—11'—12'—12 at bottom as shown in Fig. 7, and this space must be closed before top as well as bottom fishing contact with the rail ends can be secured. However it is important that the space be not 35 closed too soon as would occur if the bar's bottom fishing surface be crowned at the bottom as well as at the top. In the present invention the bar's bottom fishing surface is made uncrowned. To effect a final filling in of the bottom central fishing 40 space, it may be first stated that bars ordinarily used have considerable vertical stiffness and also springiness, the latter resulting mainly from hot-quenching in oil. Under sufficient vertical pressure the bar may deflect slightly downward but due to its springiness, the bar then presents greatly increased opposition to further deflection. Another feature of importance is that the fishing surfaces of the bars and the rail ends are inclined about 14 degrees. This is shown in 45 only Figures 4 and 6, all of the side views omitting it to simplify the drawing. It is obvious that if the bar of Fig. 8 be applied to the rail ends of Fig. 7, the first fishing contact between the bar and the rail ends will occur at the top central portion of the bar and its bottom ends. When the 50 bolts are tightened the bar rises, riding upward and inward as its bottom ends engage the inclined fishing surfaces of the rails. In Fig. 8, the bar will rise as the bolts are tightened as long as its top fishing surface is out of rail contact at its end portions, and the dropped rail ends will be forced upward by the top central fishing contact as long at least as there is not tight rail and bar fishing contact at the bottom center. It may be here 55 emphasized that Fig. 8 like the other figures, is

exaggerated. The tops of the rail ends appear to be battered down, whereas in the average worn joint, the greater part of what railroad men used to think was batter was merely droop, most of which I find may be removed to a predetermined level in a novel manner, whose final and most important stage, I will now describe. In Fig. 8, the rail ends may be raised by further tightening of the end bolts on account of the absence of top end fishing contact, and if there be tight central fishing contact at top and bottom, top fishing contact at the end portions of the bars may be secured only by flexing the ends of the bar inward by tightening the end bolts as taught in Thomson 1,208,698. The bar I employ is in general similar to that shown in Fig. 2 of Thomson, but with two important exceptions. Firstly, the bar as a whole is of normal or above normal fishing height, in addition to which, the central portion of the top fishing surface is crowned with additional metal so that it may be applied to worn rail ends. Secondly, I prefer to have the bar laterally straight when finally bolted into the joint, the lower fishing height at the ends as compared with the center being used to fit the bar to worn rail 20 ends, and not to obtain a central clamping effect by inward end flexure under end bolt tension. From my observations, I find that the forces acting on the center of a joint are so enormous that any clamping or spring action directed at the 25 ends of a bar are too impositive to accomplish any effect of consequence at center, and I desire to avoid if possible placing the bar under injurious permanent strains when not under load. Preferably the bar of Fig. 8 has no more or less lateral 30 curvature than when it is finally bolted to the rail ends. I do not wish to limit myself in any way to non-flexing of the bar ends, as some cases may make its employment advantageous, but in general I prefer not to place the bar under any 35 permanent lateral bending strains if possible. However I may employ the Thomson end flexing feature to a moderate extent to overcome slight variations of joint wear in a track, even though I prefer to avoid end flexing as far as possible, by 40 changing the height of the top crowning or the fishing height of the bar throughout its length, or both, to suit conditions of joint wear in other track as I find them. Returning to the final 45 stage of my invention, as stated previously, most of the so-called "batter" or downward depression of the rail ends in a worn joint, is a comparatively gradual droop, some of which has been removed as in Fig. 8. However, this droop is in part a permanent set which resists further raising 50 more strongly as the bolts are further tightened. It is essential that the central bottom and end top fishing gaps be closed, and to accomplish this, either the rail ends must yield and rise further with further bolt tightening, or else the bar must 55 yield and deflect downward assuming a slight longitudinal convexity conforming to the slight longitudinal concavity of the bottom fishing surface of the two rail ends. Some yielding of bar and rail ends may occur, although in moderate 60 cases of joint wear the rail ends only appear to yield. However if the bar be forced to yield it becomes a spring strongly opposing any further downward deflection. This slight yielding of the rail ends or bar or both appears to be sufficient 65 as far as I have been able to determine by trial and experiment, and a final tightening up of the bolts closes the bottom central and top end fishing gaps. To fulfill the conditions described so as to obtain the result shown in Fig. 9, it is ap- 70 75

parent that certain closely prescribed conditions must be adhered to. The bar throughout its length may be of normal fishing height for moderately worn rail ends or above normal fishing height for badly worn rail ends, but its top center portion must be crowned and its bottom surface must be uncrowned. The rail ends must be worn so that the uncrowned bottom center of the bar will provide space on final fitting to oppose any permanent set in the drooped rail ends, as previously described. This space must bear close relationship to the top end fishing spaces so that there will be tight fishing contact at the bottom center and at the tops of the end portions when the bolts are finally made tight. A shaping and shortening of the top crown appears to give better results than a longer crown, although this requires further experimentation.

In Figure 9, the joint bars have been finally tightened up, bringing the top end fishing surfaces of the bar in fishing contact with the rail ends, and substantially closing the central gap at bottom. The rail ends are now raised to their full height and can be raised no higher during the life of the joint, the top end fishing contact preventing further lifting effect. It will be seen that this is an important feature, as it prevents lifting of the rail ends beyond a predetermined height and to such an extent as to make the joint lumpy. Utilization of the slight bottom fishing surface wear of the rail ends is another novel and important feature, providing as it does, a tendency to oppose or remove slight set in the previously drooped rail ends.

Referring again to Figure 8, my aim is to close the bottom central fishing gap and the top end fishing gaps simultaneously, so that the joint will have fishing contact at these portions when the joint bolts are finally tightened up. If the top end gaps remain open the rail ends may not have been fully lifted, and the effective moment length of the bar may be insufficient. If the bottom central gap be left open, the fit of the joint under load will be reduced to below the requirement for a minimum of vertical play at center between the fishing surfaces of the bars and rail ends when the joint is under load.

The final effect of a bar crowned at the top only and in accordance with my invention, as shown in Figure 9, is to shorten the length of depression at the rail tops to 5'-19" and 5'-19" and to reduce the depth of depression at the extreme ends of the rails, so that the amount of metal to be welded on is very small, as may be noted by a comparison of Figures 9 and 5. The fact is that the depressed portions 4'-5'-19" and 4'-5'-19" of Figure 9 are really "batter"; that is, the metal of the rail head is crushed out of shape by train wheel pounding. Such a condition is not reached to any great extent until there is some fishing wear or yielding in the joint. If the joint be repaired before appreciable batter begins there would be little or no batter and the welding on of metal to the tops of the rail ends might be dispensed with altogether. The perfected method for properly maintaining important track is to make comparatively frequent repairs of the bars to the design shown in Figures 8 and 9, and dispense with rail top welding. More worn tracks with battered rail ends may be treated as in Figure 9, the amount of welding required being greatly reduced as compared with ordinary previous practice, although even in badly worn joints if the track be under secondary or light service low joints may be so improved,

even without rail-top welding, as to give fairly satisfactory service. In such cases, the worn bar may be reformed to the design described, the crowned top being greater vertically than for use in only moderately worn joints, and the bottom fishing surface being straight and in some cases slightly concaved at its center portion, no more however than would permit rail fishing contact when the joint bolts are made tight.

In the reforming of worn bars, I have varied the amount of crowning to suit various conditions of worn track. For joints moderately worn, a crown in amount between 20 to 30 thousandths of an inch has been sufficient. For badly worn joints, the crown has been increased to between 50 and 60 thousandths. In designing the crown, I have secured the best results by making it short longitudinally so as to secure ample lifting effect at the center free from interference of tight fishing contact between center and ends.

The design features in a bar such as I have described depart only slightly from a bar of ordinary type in their dimensions, but these slight differences are extremely important. A joint fit which yields vertically under load more than 3 or 4 thousandths of an inch does not fulfill the conditions required of a first class track. It will be appreciated from the preceding description that in the bar of my invention I deal with changes small in measurement, but closely controlled so as to secure predetermined results. Briefly, my invention is a specific method of repairing worn rail joints without removing the rails from track. A bar of particular design is

employed and the fishing surface wear of the rail ends at the bottom center portion is used in the final fitting to oppose set in the drooped rail ends and to lift the rail ends to a predetermined level requiring a minimum of top rail surface welding on of metal, which latter in some cases of only moderately worn joints, may be dispensed with altogether. An important feature of my bar is that it gauges the lift of drooped rail ends to a predetermined height, making it impossible to have too high joints such as might otherwise occur at any time when the end bolts are tightened up after the joint has been in service. The bar of my invention may readily be reformed from a worn bar; also it may be rolled as a new bar, the crowning of the top fishing surface being done in the rolling process or after rolling, and the bar section for convenience in manufacture being made of substantially uniform cross sectional contour throughout its length. There may be intermediate rail fishing clearances as indicated by dotted lines *x* in Figs. 8 and 9 but it is essential that the completely repaired joint have tight fishing contact for substantial lengths of its center portion and end portions at top and bottom.

What I claim is:—

1. The herein described method of repairing in track a worn rail joint in which the rail ends are worn and drooped, the same consisting in first positioning in the fishing spaces a splice bar provided with a straight undeformed bottom surface overlying the rail flanges and a top surface having a central projecting crown shaped to register with the wear depressions at the undersides of the rail heads after the raising of the drooped ends, the said bar being of less fishing height toward its end portions than at the ends of said crown leaving an initial clearance of such portions from the rail heads, said clearance being of an extent approximately equal to the

amount of the wear at the upper sides of the ends of the rail flanges, then applying an initial bolting pressure on the bar thereby to cause the drooped rail ends to rise on said crown, and 5 finally tightening the bolts causing a further rise of the rail ends on the crown until arrested by the engagement of the end portions of the bar with the rail heads and the engagement of the rail flange ends with the center bottom portion 10 of the bar whereby the top surfaces of the rails are returned into substantial alignment.

2. The herein described method of repairing in track a worn rail joint in which the rail ends are worn and drooped, the same consisting in 15 first positioning in the fishing spaces a splice bar provided with a straight undeformed bottom surface overlying the rail flanges and a top surface having a central projecting crown shaped to register with the wear depressions at the under- 20 sides of the rail heads after the raising of the

drooped ends, the said bar being of less fishing height toward its end portions than at the ends of said crown leaving an initial clearance of such portions from the rail heads, said clearance being of an extent approximately equal to the 5 amount of the wear at the upper sides of the ends of the rail flanges, applying an initial bolting pressure on the bar thereby to cause the drooped rail ends to rise on said crown, next finally tightening the bolts causing a further rise 10 of the rail ends on the crown until arrested by the engagement of the end portions of the bar with the rail heads and the engagement of the rail flange ends with the center bottom portion 15 of the bar whereby the top surfaces of the rails are returned into substantial alignment, and then welding metal onto the top corners of the rail ends to restore the original level surface.

GEORGE LANGFORD. 20
